UNITED STATES PATENT OFFICE.

HIRAM HERROLD AND AMES D. HERROLD, OF LUTHER, OKLAHOMA.

THROTTLE-CONTROLLING MECHANISM FOR AUTOMOBILES.

1,218,939.

Specification of Letters Patent. Patented Mar. 13, 1917.

Application filed September 21, 1916. Serial No. 121,493.

To all whom it may concern:

Be it known that we, HIRAM HERROLD and AMES D. HERROLD, citizens of the United States, residing at Luther, in the county of 5 Oklahoma, State of Oklahoma, have invented certain new and useful Improvements in Throttle-Controlling Mechanisms for Automobiles; and we do hereby declare the following to be a full, clear, and exact description 10 of the invention, such as will enable others skilled in the art to which it appertains to make and use the same.

This invention relates to improvements in automobile controlling mechanisms, and 15 particularly to gasoline feed controls.

The principal object of the present invention is to provide a novel and simple mechanism which will cause the closing of the throttle, completely, by the same movement 20 which applies the brake, and which is especially adapted for use on Ford automobiles.

Another object of the invention is to provide a novel means for controlling the gasoline feed by hand or foot, each means being 25 arranged to be actuated independently and without interference with the other means.

Another object is to provide a novel means which is adapted to be connected with the brake pedal of the automobile for permitting 30 the automatic closing, to the fullest extent, of the throttle when the brake is being applied.

Other objects and advantages will be apparent from the following description when 35 taken in connection with the accompanying drawing.

In the drawings:

Figure 1 is a top plan view of the front portion of a Ford automobile, the casing 40 being removed.

Fig. 2 is a side elevation, the casing being removed.

Fig. 3 is a vertical sectional view on the line 3—3 of Fig. 2.

Fig. 4 is a perspective view of the brake pedal.

Fig. 5 is a perspective view of the angle arm and supporting bracket therefor.

Fig. 6 is a perspective view of the parts 50 connected with the gas control lever.

Referring particularly to the accompanying drawing 10 represents the throttle to which is pivotally connected a link 11 which extends transversely of the front of the automobile. The steering column is represented 55 at 12, and carries the usual gas controlling

rod 13. The lower end of this rod is formed with an eye 14, through which the before-mentioned link 11 is slidably disposed, the said link beyond the eye being formed with 60 a head 15 to prevent the link from passing therethrough in one direction. Secured to the water pipe 16, which leads from the radiator to the engine cylinders, by means of a clamp, is a supporting bracket 17, and 65 mounted on this bracket is a pivotally supported angle lever 18, to one arm of which is pivotally connected one end of a second, but shorter link 19, said link 19 being pivotally connected at its other end to the throttle 70 valve, coincidently with the point of attachment of the first link. The brake pedal 20 is formed with a downwardly projecting extension 20' which is connected to a crank portion 21 of the controlling rod or shaft 75 22, which has on one end the emergency brake lever 23. A spring 24 connects the brake pedal lever 20 with the chassis of the automobile, and holds the said pedal normally in rearwardly disposed position. Piv- 80 otally connected to the upper portion of the pedal is a forwardly extending link or lever 25, the forward end of which is slidably disposed through an eye 26 formed in the other arm of the bell crank or angle lever 18, said 85 link being also formed with a head 26' on its forward end to limit its rearward movement through the said eye. A rearwardly extending leaf spring 27 is secured to the forward portion of the chassis and has its 90 rear end connected to the head 15 of the link 11 by means of a short link 28. The heads 15 and 26' are both adjustable for a purpose which appears later.

It is well known that the throttle valve of 95 the engines of automobiles do not entirely close when the control rod is thrown to closed position. Also, on Ford automobiles the gasoline control is accomplished solely by the rod on the steering column; there being no provision for controlling the gasoline by means of the foot. It is, therefore, the principal object of the present invention to provide a mechanism whereby the gasoline can be controlled by the foot when the brake 100 is being applied.

The operation of the present device may be briefly stated as follows:

When it is desired to coast down a hill 110 without applying the brake, the foot is placed on the brake pedal and the same pushed forward to a point intermediate that

of normality or rest, and the braking position. This movement of the pedal will permit the link 25 to slide idly through the eye in the arm of the angle lever 18, and by reason of the spring 27 and the link which connects it with the link 11, said link 11 will be pushed in the direction of the throttle valve and move the latter into completely closed position. In normal position, the link's head 15 does not engage with the eye of the controlling rod, thus permitting the said link to slide through the eye without affecting the position of the controlling rod 13. Thus the automobile can coast without applying the brakes, and with the engine running.

By a further pressure on the brake pedal the brakes can be applied to retard or stop the car. Thus we have provided a simple and novel device which can be readily applied to the present Ford automobiles, whereby the gasoline supply to the engine can be conveniently controlled by the foot of the operator irrespective of the usual 25 hand control.

What is claimed is:

1. A throttle and brake mechanism for an automobile including a manually operable throttle means, an angle member, connections between one arm of the angle mem- 30

ber and the throttle, a brake pedal normally and resiliently held in inoperative position, and a link carried by the brake pedal and slidably connected with the other arm of the angle lever.

35

2. A throttle and brake mechanism for an automobile including a throttle valve, means for opening and partially closing the valve, an angle lever operatively connected with the valve and movable therewith, an angularly extending apertured portion on one end of one arm of the angle lever, a brake pedal having a depending extension, an emergency brake member, a link pivotally connected to the emergency member and 40 slidable through the said extension, and a link pivotally connected to the brake pedal and slidable through the apertured portion of the angle lever, said link being formed with a head for operative engagement with 45 the angle lever to move the same in one direction.

50

In testimony whereof, we affix our signatures in the presence of two witnesses.
